UNITED STATES PATENT OFFICE.

LOUIS KOSSUTH JOHNSON AND ABBOT AUGUSTUS LOW, OF NEW YORK,
N. Y., ASSIGNORS TO THE ALDEN TYPE MACHINE COMPANY, OF SAME
PLACE.

TYPE-SETTING APPARATUS.

SPECIFICATION forming part of Letters Patent No. 639,244, dated December 19, 1899.

Application filed April 16, 1897. Serial No. 632,400. (No model.)

To all whom it may concern:

Be it known that we, LOUIS KOSSUTH JOHNSON and ABBOT AUGUSTUS Low, citizens of the United States, residing in the city of New York, (Brooklyn,) in the county of Kings and State of New York, have invented certain new and useful Improvements in Type-Setting Apparatus, of which the following is a specification, sufficient to enable others skilled in the art to which the invention appertains to make and use the same.

Our improvements relate to apparatus for forwarding types from the lower end of a type-containing channel into position for removal to the compositor's stick by hand and is adapted to effect the presentation of a single type or a plurality of types arranged to form a word or other prescribed combination of characters.

In its general arrangement and operation our present construction embodies the essential features of prior applications for patents made by us as Serial No. 616,938, filed December 24, 1896, and Serial No. 614,165, filed December 2, 1896, our present improvements being designed mainly to render the apparatus more accurate and delicate in operation.

A distinguishing feature of our present invention consists in providing the actuating-lever by which the type-forwarding mechanism is controlled with a gravity-latch for engagement with the pawl on the power-clutch, so arranged in conjunction with a stationary part of the frame that said gravity-latch is thrust forward at the proper time to encounter the outer end of the pawl and afford a comparatively broad bearing therefor and quickly withdrawing from contact with said pawl when the withdrawal of type previously forwarded releases the actuating-lever. Thus by augmenting the extent of contact between the said gravity-latch on the actuating-lever and the pawl on the power-clutch, at the same time quickening the time of release between said parts, we adapt the apparatus to the forwarding of single types of minimum thickness, the comparatively slight movement of the actuating-lever caused by the withdrawal of such narrow types being compensated for by the gravity-latch, so

that the operation of engaging and releasing the power or type-forwarding mechanism is rendered certain and uniform for all types or combinations thereof.

Another feature of our present invention consists in elevating the forward end of the actuating-lever by depressing its rear end at the proper time by means of a controlling-arm engaging with the upper side of the lever and having a motion parallel to and coincident with the type-pusher, the parts being so timed that the gravity-latch is thrust into the path of the advancing end of the pawl of the clutch simultaneously with the raising of the type or finger-piece to confine the forwarded types between it and the upper bearings. Incidentally in this connection our invention includes the making of this controlling-arm adjustable both vertically and horizontally in the plane of the actuating-lever for the purpose of effecting an accurate adjustment of the parts with relation to each other, so that their operation will be delicate and sensitive to the removal of the thinnest types as well as to thicker types or word combinations.

Still another improvement consists in the special arrangement of means for adjusting and controlling the type-finger on the forward end of the actuating-lever and in the form of the pivotally-suspended type-bearing above.

Our invention also includes a lateral support for the type-channels, said support being pivotally connected to channel-holder and confining the channel and supporting it laterally by spring-pressure or by a locking-screw, if desired.

The invention also involves certain other special features in the construction, arrangement, and combination of parts, as hereinafter set forth.

In the accompanying drawings, Figure 1 is a sectional elevation showing the parts at rest. Fig. 2 is a similar view of the forward end of the apparatus, showing the type-finger adjusted for one type. Fig. 3 is a sectional elevation of the reverse side of the device, the parts being at rest. Figs. 4 and 5 are respectively a side elevation and a top view of the pusher-slide and connections.

In the drawings, A represents the stationary frame of the apparatus, of which the table *a* is a part. This table *a* is formed with sockets *a'* for the reception of the tenons *h* of the channel-holders *H*, as heretofore.

The type-containing channel *C* is formed at its lower end with the horizontal type-supporting shoulders *c* on one side of the vertical slot *c'*, made in the path of the pusher-blade *p*, which path extends between said horizontal type-shoulder *c* and the opposed wall of the channel *C*.

The type-channel *C* is supported by and upon the slide *S*. This slide *S* fits in a vertical groove *h'*, formed in the side of the holder *H*, and is made adjustable vertically by suitable means, as by the vertical set-screw *s*, engaging with a female screw-thread formed in the lower part of the holder, as shown in the drawings, which construction is preferable in that the sides of the holder are left free and unobstructed, while the adjustment of the slide can be readily effected when the holder *H* is removed from the table *a*. It is to be understood that this adjustment of the slide *S* is for the purpose of regulating the position of the type-shoulder *c* upon the channel *C* with relation to the position of the pusher-blade *p*, the path of which is prescribed as in structures heretofore described by us. The channel is held in a vertical position by the wall *h³* of the holder upon one side and by the lateral arm *W* on the other. This arm is pivotally supported on the rear of the holder *H* and tends constantly to press against the side of the channel by reason of the action of the spring *w*, which compensates for differences in the thickness of the channels which may be used in the holder *H*. The spring *w* may be of sufficient stiffness to maintain the channel steadily in position upon that side of the holder, or it may be supplemented by a set-screw *w'*, by which the arm *W*' may be positively held against the wall of the channel *C*.

The front guard *h⁴* of the holder *H* is formed at its lower end with the pivoted upper heel *g*, which acts, in conjunction with the finger-piece *f* below, to hold the advanced types until they are withdrawn by the compositor. This act of withdrawing the types releases the lever *L*, the rear arm of which, carrying the latch *J*, is heavier than the forward arm, carrying the finger-post *O*, so that the latch *J* instantly releases the pawl *e* and starts the type-forwarding mechanism.

P is the reciprocating pusher-slide, to which the pusher-blade *p* is attached. A rear extension *p'* of this pusher-slide *P* carries the vertical rod *V*, the lateral arm *v* of which rests against and controls the inclination of the actuating-lever *L*. The rod *V* is held in a bracket *B* on the rear extension *p'* by a screw *b*, which admits of the vertical adjustment of said rod *V*, while the bracket *B* is itself adjustable horizontally upon the rear extension *p'* by the screws *b' b'*, so that the

position of the lateral arm *v* may be varied and regulated with relation to the plane of the actuating-lever, and especially with relation to the cam-surface *l* on said lever. 70

The pusher-slide *P* is connected to the eccentric *E* by the pitmen *F* and eccentric-strap *f'*. The eccentric *E* is loose upon the power-shaft *I*, except when coupled thereto by the pawl *e*, which engages with any of the shoulders *i i* on said shaft when not held out of engagement therewith by the upper end of the gravity-latch *J* on the actuating-lever *L*. The shaft *i* is in constant rotation, so that directly 80 the pawl *e* is released it encounters and engages with one of the shoulders *i*, and thereby carries the eccentric *E* around with the shaft until the pawl *e* is again released, which is at the end of a single rotation, provided a type 85 has been forwarded between the upper heel-guard *g* and the type-finger *f*, in which position the type holds the actuating-lever *L* in such relation to the stationary bar *R* that the gravity-latch *J* tilts backward, with its upper 90 end in the path of the outer end of the pawl.

The protruding and retracting of the upper end of the gravity-latch *J* is effected by reason of the contact of its cam-surface *j* with the stationary bar *R* or equivalent, the lower end 95 of said latch *J* being pivoted to the actuating-lever *L* in such position that said cam-surface is held by gravity in constant engagement with said stationary bar *R*.

The actuating-lever *L* is formed with a slot 100 *l* on its under side, so as to straddle the fulcrum *K*, this construction admitting of the convenient withdrawal of the lever or insertion in position without disturbing adjoining parts of the apparatus. 105

The type-finger *f* is mounted upon the upper end of a stud *f'*, which is held adjustably in the pivoted post *O* by a set-screw *o*. A set-screw *N* on top of the lever is used in conjunction with the spring-bolt *M*, mounted 110 upon the lower side of said lever, the set-screw *N* limiting the thrust of the spring-bolt *M*, so as to relieve the type-finger *f* of undue frictional contact with the front of the table *a*.

What we claim as our invention, and desire 115 to secure by Letters Patent, is—

1. In a compositor's type-case of the character designated, the combination with the type-forwarding blade having a prescribed path of reciprocation, and with a supporting-table, of a type-containing channel, a channel-holder formed with a channel-supporting slide, and a screw for supporting said slide and effecting the vertical adjustment thereof, substantially in the manner and for the purpose described. 120

2. In a compositor's type-case of the character designated, the combination with the type-forwarding blade having a prescribed path of reciprocation and with a supporting-table and type-containing channel, of a type-supporting finger pivoted to the end of the trigger-lever which controls the actuating mechanism, a spring in said lever for thrust- 125 130

ing said type-finger inward and an adjustable device on said lever for limiting the motion of the finger-lever, substantially in the manner and for the purpose described.

5 3. The combination with a type-containing channel-holder, supporting-bed, type-forwarding mechanism, type-finger, and actuating mechanism, of a cam-surface on the upper side of said actuating-lever, and a 10 pressing-arm for engagement with said cam-surface, said depressing-arm being mounted upon the pusher-slide and having a motion parallel thereto, substantially in the manner and for the purpose described.

15 4. The combination with a type-containing channel, holder, supporting-bed, type-forwarding mechanism, type-finger, and actuating mechanism, of a cam-surface on the upper side of said actuating-lever, and a 20 pressing-arm for engagement with said cam-surface, said depressing-arm being mounted adjustably upon the pusher-slide and having a motion parallel thereto, substantially in the manner and for the purpose described.

25 5. The combination with the type-containing channel, channel-holder, type-supporting table, type-forwarding mechanism, type-finger and actuating-lever, of a gravity-latch on said lever acting in conjunction with a 30 stationary part of the machine, to engage and disengage the pawl on the power-clutch mechanism, substantially in the manner and for the purpose described.

6. The combination with the actuating 35 parts of the type-case, of the lever L, formed with the cam-surface l, the vertical rod V, formed with the lateral projection v, the brackets B, supporting said rod V, adjustably and itself adjustable horizontally upon

the pusher-slide P, the whole arranged and 40 operating substantially in the manner described.

7. The combination with the type-supporting surfaces and operative parts of the mechanism, of the type-finger F, upon the stud F', 45 set-screw o, the post O, pivotally connected to the end of the lever L, and a spring-bolt M, and limiting-screw, the whole arranged and operating substantially in the manner and for the purpose described. 50

8. The combination with the operative parts of the apparatus of a stationary bar R, latch-lever J, pivotally connected to the actuating-lever L, and the pawl e, pivotally connected to the eccentric E, the whole arranged 55 and operating substantially in the manner and for the purpose described.

9. The combination with the channel-holder substantially such as described, of a lateral support on one side of the type-containing 60 channel, said support being pivotally connected to the holder, and being provided with a spring which tends constantly to press the holder against the side of the type-containing channel substantially in the manner and 65 for the purpose described.

10. The combination with the holder H, having the side wall h³, of the lateral channel-support, W, pivotally connected to the holder, the spring w, and the set-screw W', 70 the whole arranged and operating substantially in the manner and for the purpose described.
